(57) CLAIM

An ornamental design for a wristband, as shown and described.

DESCRIPTION

FIG. 1 is a perspective view of a wristband; FIG. 2 is a top plan view of the wristband of FIG. 1; FIG. 3 is a bottom plan view of the wristband of FIG. 1; FIG. 4 is a front elevational view of the wristband of FIG. 1; FIG. 5 is a rear elevational view of the wristband of FIG. 1; FIG. 6 is a right side elevational view of the wristband of FIG. 1; and, FIG. 7 is a left side elevational view of the wristband of FIG. 1.

The broken lines, shown as dot-dot-dot lines, depict portions of the wristband that form no part of the claimed design. The cross-hatching shading in the figures is fragmentarily shown for convenience of illustration, it being understood that the cross-hatching shading is uniformly continued over the surface on which it appears.
